UNITED STATES PATENT OFFICE.

HEWLET T. SMITH, OF OXNARD, CALIFORNIA.

TOOL-WRENCH.

1,399,089.

Specification of Letters Patent.

Patented Dec. 6, 1921.

Application filed November 18, 1920. Serial No. 424,807.

To all whom it may concern:

Be it known that I, HEWLET T. SMITH, a citizen of the United States, residing at Oxnard, in the county of Ventura and the State of California, have invented new and useful Improvements in Tool-Wrenches, of which the following is a specification.

This invention relates to tool wrenches, and more particularly to apparatus for screwing and unscrewing or joining or unjoining tools used in oil well drilling in the so-called standard oil reciprocating drilling method. In this method the tools are suspended by a cable from the walking beam, and are given vertical reciprocation in the well, thus cutting, chipping or pounding away the formation and developing the well hole. The tools are connected together in what is called a "string," often including a plurality of such tools, such as bits, sinker bars, stems and jars. In order to screw these together or unscrew them and disconnect them, heavy and powerful wrenches are employed, and it requires considerable power to operate such wrenches. Ordinarily one such wrench is applied to a string of tools beneath a tapered joint, and the other wrench is applied to the tools above such tapered joint or coupling, which tapered joints or couplings it is to be understood are connected with the tools and have screw threads. One wrench is ordinarily held stationary, and the other wrench is operated to produce the rotation requisite to couple or uncouple the tools at such threaded taper joint. In connection with such use of the wrenches what is called a floor circle is ordinarily employed, this consisting of a toothed quadrant or segmental rack mounted upon the floor of the derrick at the mouth of the well. Mounted upon this rack is a toothed ratchet device to which is applied a lever by which the ratchet device is operated to cause it to traverse such segment or rack which is arranged with a string of tools at the center of the segment or quadrant. At one end of this rack is provided a stop against which bears one wrench, and the other, preferably the upper wrench, bears against the ratchet device. Thus as the ratchet device is operated along the floor circle or toothed segment it carries with it the outer end of the upper wrench and either screws or unscrews the tools at the tapered joint. The

pressure of the two wrenches upon the ratchet device and the stop mentioned tends to cause the floor circle to wedge or slide inwardly upon the floor of the derrick and thus reduce the leverage upon the wrenches so as to render the operation of the device difficult or impossible. To prevent this inward creeping of the floor circle and ratchet device, it has been the practice to use blocks or sticks of wood as a prop or spacer between the string of tools suspended at the mouth of the hole, on the one hand, and the floor circle on the other hand. When this is done there is a pressure imposed upon the jaw portion of the wrench arms due to the long leverage. Ordinarily the jaw will crack or give way at some angle point in said jaw. When this occurs the string of tools may tend to rotate in an opposite direction and it is necessary to apply a new wrench and commence the work over. In order to prevent breaking of the jaw of the tool wrench I have provided a closure means which has a pivotal connection with the free end of the jaw, and which closure means co-operates with the lever arm of the tool wrench. In detail I may say that my improved wrench includes a lever having a jaw member pivotally joined thereto and a closure member pivotally connected with the free end of the jaw member and co-operating with the opposite end of the jaw member and with the lever arm. Inter-engaging means are provided on both legs of the jaw member, on the closure member and upon the lever arm, so that when the jaw surrounds the tapered joint of a string of tools and the closure member is in locked position, upon operating the ratchet device associated with the floor circle, any pressure that would come upon the jaw and tend to break the same would be evenly distributed around the jaw and through the closure member. In other words, the closure member and the jaw member as well as the lever arm co-operate in such a manner as to distribute all stress.

The invention concerns the several parts and features mentioned and their combination and association and particularly the tool wrench, all as hereinafter described, shown in the drawing, and finally pointed out in claims.

The invention consists in the novel and useful provision, formation, combination,

association, application and relative arrangement of parts, members and features, all as hereinafter so described, shown and claimed, as above mentioned.

5 The invention has for its objects to provide means of the nature stated which will be superior in point of relative simplicity and inexpensiveness of construction, taken in conjunction with reliability and 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 members 38 and 39 contact with shouldered portions 50 of the end 33, the member 45 will interlock in the V-shaped portion 42 and have its edge 46 in contact with the edge 47 of the member 43. The end 51 of the member 36 is provided with a transverse grooved portion 52 and with a hook member 53, which hook member is provided with a jaw portion 54, the hook member being of a thickness corresponding to the width of the groove 52. Within the recessed portion 21 of the arm 15 is a notch 55, said notch forming two wall members 56 and 57. The closure 36 is adapted to swing upon the pivot 41 and allow the hook member 53 to engage the notch portion 55 so that the jaw portion 54 will have one of its faces as 58 in engagement with the wall member 56. Referring to Fig. 4 it is to be noted that the wall member 57 simply acts as a partition between the lever arm 13 and the jaw 53. In Fig. 4 it is to be noted that the closure member 36 is transversely recessed as at 59. When the lever arm 13 is in the position as illustrated in Fig. 3 the closure or gate member 36 may be thrown into position so that its jaw 53 will engage the notch portion 55, whereupon the lever arm 13 may be closed as illustrated in Fig. 4, at which time the jaw 26 will enter the recess 59 of the closure 36. It is intended that an edge as 60 of the jaw should coöperate with a face as 61 of the recess 59. The closure member 36 is likewise provided with a handle member 62 for opening and closing the closure member.

The plate 29 upon the lever arm 13 may be welded thereon or it may be integrally formed with the lever arm when the lever arm is cast, or the lever may be notched at a portion and then bent over to form two ears which would form the plate 29.

Referring to Fig. 4 it is to be observed that when the closure member 36 is in position so that it coöperates with the jaw 14 and with the lever arm 13, that the member 45 will coöperate with the member 43, the jaw 26 with the recess 59, the hook 53 with the notch 55, and the plate 29 with an edge of the arm 15. Thus when the jaw portion 50 engages the taper joint 20 the various members just mentioned will coöperate and inter-engage with one another, so that any stress that would come upon the jaw members would be resolved throughout the arms 15, 16 and the closure 36; thus making a complete circuit. As a consequence breakage of the jaw member 14 at a point as *a* or *b* is positively prevented. The jaw 26 coöperating with the recess 59 in the closure 36 prevents the closure from opening when the wrench is in position as shown in Fig. 1. The shoulder 50 between the member 16 and the member 36, also tends to prevent a further rotation of the member 36, and to this end it is to be noted that the coöperation of the hook

member 53 within the portion 55 also resists rotation. The member 45 in coöperation with the member 43 prevents a lateral stress when the arms 15 and 16 try to spread apart, and to this end the jaw 26 coöperates with the face 61 in the recess 59 and the faces 56 and 58 likewise coöperate. The lever arm 13 is prevented from further movement by having its lateral edge as 27 coming into contact with the shoulder 28, as well as having the plate 29 coming into contact with the lateral edge of the arm 15. Thus, regardless of the stress imposed upon the arms 15 and 16, it is to be noted that the stress is resolved in all directions, and it is also to be noted that practically all shearing stress is relieved from the pivot points 22 and 41.

It is obvious that many changes and variations and modifications may be made in departure from the particular description and showing of the accompanying drawing, in adapting the invention to varying conditions and requirements of use and service, all without departing from the true spirit of the invention.

Having thus disclosed my invention, I claim and desire to secure by Letters Patent:

1. In a wrench, the combination with a lever and jaw member associated therewith, of a closure member pivotally joined to said jaw member, and inter-engaging means on said members for locking said members together in stress resisting relation; certain of said means on the jaw member and closure member being adjacent the pivotal connection to minimize stress thereon.

2. In a wrench, the combination with a lever, of a jaw member having one of its ends pivotally joined thereto, a closure member pivotally joined to the opposite end of the jaw member, and inter-engaging means on said members for locking said members together in stress distributing formation; said end of the jaw member which coöperates with the lever being recessed for reception of a portion of said lever, said lever being provided with a part adapted to bear against a lateral edge of said jaw member; said lever likewise being provided with a jaw member and there being a groove formed in said closure member for reception of said jaw member.

3. In a wrench, the combination with a lever, of a jaw member having one of its ends pivotally joined thereto, a closure member pivotally joined to the opposite end of the jaw member, and inter-engaging means on said members for locking said members together in stress distributing formation; said closure member being bifurcated at one end thereof and said jaw member being provided with a tongue for reception within the bifurcated portions, certain of the inter-engaging means being located on

the said tongue and within the bifurcated portion.

4. In a wrench, the combination with a lever and jaw member associated therewith, of a closure member pivotally joined to said jaw member, and inter-engaging means on said members for locking said members together in stress resisting relation; a portion of said jaw member being recessed to form 10 a tongue therein, and a hook provided on the free end of said closure member for coöperation with the tongue member in the recessed portion of the jaw.

5. In a wrench, the combination with a lever, of a jaw member having one of its 15 ends pivotally joined thereto, a closure member pivotally joined to the opposite end of the jaw member, and inter-engaging means on said members for locking said members 20 together in stress distributing formation; said end of the jaw member which coöperates with the lever being recessed for reception of a portion of said lever, said lever being provided with a part adapted to bear 25 against a lateral edge of said jaw member; said lever likewise being provided with a jaw member and there being a groove formed in said closure member for reception of said jaw member; there being a 30 tongue within the recessed portion of the jaw member, and the free end of the clo-

sure member being provided with a hook for coöperation with the tongue member.

6. In a wrench, the combination with a lever member and jaw member associated 35 therewith, of a closure member pivotally joined to said jaw member, and means on the closure member adapted to interlock with means on the jaw member and lever member when the closure member is closed for distributing stress on the jaw member.

7. In a wrench, the combination with a lever member, of a jaw member having one of its ends pivotally joined thereto, a closure member pivotally joined to the opposite end 45 of the jaw member, and means on the closure member adapted to interlock with means on the jaw member and lever member when the closure member is closed for distributing stress on the jaw member; said closure 50 member being formed with a groove, and the said lever member being provided with a jaw portion adapted to enter said groove for maintaining the closure member in closed position.

In testimony whereof, I have signed my name to this specification in the presence of two subscribing witnesses.

HEWLET T. SMITH.
